UNITED STATES PATENT OFFICE.

HARRY H. JONES, OF FULLERTON, CALIFORNIA.

ROTARY REAMER.

Application filed June 26, 1924. Serial No. 722,458.

To all whom it may concern:

Be it known that I, HARRY H. JONES, a citizen of the United States, and resident of Fullerton, in the county of Orange, State of California, have invented new and useful Improvements in a Rotary Reamer, of which the following is a specification.

This invention relates to well drilling and pertains to a cutting tool having a guide 10 for insuring the cutting of a straight hole.

When drilling with rotary bits or rock drills, especially in large holes, it is difficult and often impossible to prevent the drills or bits from dodging or sidetracking around boulders or hard spots and producing a zig-zag hole. It is difficult and sometimes impossible to insert a casing in such a hole. It then becomes necessary to ream and straighten the hole. Due to the flexibility 15 of rods and pipes to which the reamers are attached, it has been difficult to straighten the hole, because of the reamer following the hole.

The present invention utilizes a guide the full size of the hole to direct the advance 20 of the cutting tool. It is the primary object of this invention to provide a tool of this character, so constructed that the drill pipe or rod can flex through the guide, thereby putting no undue strain on threads 25 or connections. It has been found that if said flexibility is not present, there is a great tendency for the drill pipe or rod to break at its point of connection with the guide. In addition to the broader objects of this 30 invention, there are certain details of construction which insure an economical, simple, easily manipulated, and durable structure.

These objects together with other objects and corresponding accomplishments are obtained by means of the embodiment of my invention illustrated in the accompanying drawing, in which:

The figure is an axial section through a 45 complete reamer.

Referring more particularly to the drawing, the usual drill pipe or stem is indicated by 1. The stem is connected by a tool joint 50 2 to a special drill collar 3. The collar is internally threaded at its lower end to receive the tapered end of a bit or other cutting tool. It is reduced in diameter at the lower end and externally threaded to receive a lock nut later described. In the present instance, I have shown a fish tail

bit 4 mounted upon the end of the drill collar. The construction just described is that well known in the drilling art, wherein, circulation fluid may be supplied through 60 the drill pipe and bit to wash away the cuttings.

Mounted over the drill pipe and collar is my guide consisting of a slip bushing 5 having a bore through which the drill pipe is 65 passed. There is a clearance between the bore of the bushing and the drill pipe sufficient to provide a loose fit and to permit flexing of the drill pipe through the bushing. Eyebolts 6 are mounted upon the bushing 70 for convenience in handling the latter. The bushing is externally threaded for securing a collar 7 thereto. A joint 8 of casing is secured to the collar and is of substantially the same diameter as the hole being 75 drilled. In order to prevent the casing backing off, pins 9 are inserted through the collar 7 and casing 8. A special sleeve or reducing bushing 10 is secured to the bottom of the casing 8 and snugly engages the 80 reduced portion of the drill collar. Mud holes 11 are provided to drain out any mud entering the guide shell 8. A lock nut 12 is mounted upon the bottom of the drill collar securing the guide in place and is 85 pinned to the bushing 10.

It is obvious that the guide will occupy a space within the hole, brace itself and maintain the drill pipe and associated parts in a straight line advance. The clearance between the bushing 5 and drill pipe is sufficient so that there is no bending strain concentrated at the point of entrance of the drill pipe through the guide or bushing.

The method of operation of the device in 95 reaming and straightening a hole is obvious. The slush for circulation is delivered by the pump at the point the work is being done the same as when a new hole is being drilled. In case boulders or inclined hard formations 100 are encountered, the reamer may be used to insure a straight hole in initial drilling, but this will not be advisable except in special cases.

What I claim is:

1. A device of the character described comprising the combination of a rotary cutter having a stem, a relatively long guide shell mounted on said stem, said guide shell being snugly secured to said stem at the 110 lower end and loosely secured to said stem at the upper end so as to permit flexure of

said stem, said stem being secured to said cutter for rotation of the latter and extending upwardly beyond said shell.

2. A device of the character described comprising the combination of a rotary cutter having an operating stem, a relatively long guide shell of substantially the same diameter as the bore to be cut mounted on said stem, there being a snug fit between 10 said stem and said shell adjacent the cutter and a loose fit between said stem and said shell adjacent the upper end of the latter so as to permit flexure of said stem, said stem being secured to said cutter for rotation of the latter and extending upwardly beyond said shell.

3. A device of the character described comprising the combination of a rotary cutter having an operating stem, a tubular 20 relatively long guide shell of substantially the same diameter as the bore to be cut, bushings at the upper and lower ends of said shell, the upper bushing providing a loose fit with said stem so as to permit flexure 25 thereof, the lower bushing snugly fitting said stem so as to securely hold the latter, said stem being secured to said cutter for rotation of the latter and extending upwardly beyond said shell.

30 4. A device of the character described comprising the combination of a cutter hav-

ing a drill collar secured thereto and a drill pipe secured to said collar, a joint of casing of substantially the same diameter as the hole bored by said cutter disposed about said drill collar and drill pipe, a slip bushing secured to the upper end of said casing and having a bore loosely fitted to said drill pipe, a slip bushing and reducer secured to the lower end of said casing and having a bore snugly fitted to said drill collar, said drill pipe being secured to said collar for rotation of said cutters.

5. A device of the character described comprising the combination of a cutter, a 45 drill collar secured thereto and reduced in diameter at the lower end thereof, a drill pipe secured to said collar, a joint of casing disposed about said drill collar and drill pipe, a slip bushing secured to the upper end 50 of said casing and having a bore loosely fitting said drill pipe, a slip bushing and reducer secured to the lower end of said casing and mounted on the portion of said drill collar of reduced diameter, and a lock 55 nut snugly securing the said slip bushing and reducer to said drill collar.

In witness that I claim the foregoing I have hereunto subscribed my name this 19th day of June, 1924.

HARRY H. JONES.
